UNITED STATES PATENT OFFICE.

DONALD M. MCLEAN, OF BOSTON, MASSACHUSETTS.

BUCKLE.

SPECIFICATION forming part of Letters Patent No. 727,992, dated May 12, 1903.

Application filed August 26, 1902, Serial No. 121,021. (No model.)

To all whom it may concern:

Be it known that I, DONALD M. MCLEAN, of Boston, in the county of Suffolk and State of Massachusetts, have invented certain new and useful Improvements in Buckles, of which the following is a specification.

This invention relates to buckles, and particularly to the type known as "lock-buckles;" and the object of the invention is the production of a simple and cheap construction whereby a rigid tongue will firmly hold a strap.

A further object is to provide such a buckle which will enable an ordinary padlock to be employed without risk of breaking the padlock or parts of the buckle in use, due to the padlock being struck by any external object.

To these ends the invention consists in the construction substantially as hereinafter described and claimed.

In the drawings, Figure 1 represents a plan view, and Fig. 2 a longitudinal section, of one embodiment of the invention. Figs. 3 and 4 represent views similar to Fig. 2, but each illustrating a different embodiment of the invention. Fig. 5 represents a perspective view of the form of buckle shown in section in Fig. 3.

30 The same reference characters indicate the same parts in all the figures.

Referring first to Figs. 1 and 2, the frame of the buckle is shown as of an ordinary type having side bars *a* and cross-bars *b*, *c*, and *d*, respectively, the cross-bar *c* serving as the means for attachment of one end of a strap *x* in a common manner, the cross-bar *d* being that underneath which the free end of the strap is passed, and the cross-bar *b* forming 40 a loop to confine the end *y* of the strap. In this form the rigid tongue *e* consists simply of an arm projecting upward from the cross-bar *c* and integral therewith and preferably at an angle toward the cross-bar *d*. The outer 45 end of the tongue *e* is formed with a perforated enlargement *f* to receive the hasp of a padlock *g*, which latter may be of the ordinary type and is represented somewhat conventionally. It will be observed that the 50 outer end of the tongue projects out of the

plane of the cross-bars of the buckle, thus permitting the hasp of the padlock to freely rotate in the perforation of the enlargement of the tongue, so that the padlock may rest either as shown in the drawings or may swing 55 over to rest upon the buckle without bending or breaking the padlock or its hasp or any portion of the buckle.

The form of buckle shown in Figs. 3 and 5 differs somewhat from the form just described 60 in that the tongue *e* is shorter and thicker and formed with a more pronounced enlargement *f* and also in that the cross-bar *b* is designed to be connected with the strap *x*. A holding-loop *x'* is shown in this figure for the end of 65 the strap *y*. In each form shown the enlargement of the tongue is such as to form a shoulder *h* at the back thereof, said shoulder engaging the top of the strap *y* at the end of the slot or hole in the latter, and thus preventing 70 the strap from slipping off from the tongue whether a lock *g* is employed or not. The form shown in Figs. 3 and 5 is particularly serviceable in this respect, as the tongue inclines somewhat rearwardly.

In the form represented in Fig. 4 the construction is somewhat similar to that shown in Fig. 2 in so far as the rigidity of the tongue is concerned. In this form, however, the portion of the buckle back of the cross-bar *c* is 75 omitted, thus simply doing away with the metallic loop for confining the strap end. In this form the tongue is not integral with the cross-bar of the buckle, but is preferably riveted to it, so as to be practically as rigid as 80 the other forms shown.

The cross-bar *d* of the buckle may be provided with the usual antifriction-sleeve *h*, as represented in Fig. 4.

In each form shown the construction is such 90 that the padlock may swing freely over, so as to rest either forward or back of the tongue, without liability of injuring either member or the connection between them, and when it is not desired to lock the strap the padlock 95 may be entirely removed and the buckle then used in the ordinary manner, the shoulder at the back of the tongue being ample to prevent accidental displacement of the strap.

As will be readily understood, a chain might 100

be substituted for the strap, if desired, without departing from the spirit of the invention.

enlargement may swing forward or back on the buckle.

10

I claim—

A buckle having a rigid tongue provided with a perforated enlargement at its end, said enlargement projecting out of the plane of the cross-bars of the buckle, whereby a padlock having its hasp in the perforation of the

In testimony whereof I have affixed my signature in presence of two witnesses.

DONALD M. MCLEAN.
